UNITED STATES PATENT OFFICE.

LEIGH S. BACHE, OF BOUNDBROOK, NEW JERSEY, ASSIGNOR TO THE GRAPHITE LUBRICATING COMPANY, OF BOUNDBROOK, NEW JERSEY, A CORPORATION OF NEW JERSEY.

OILLESS SPINDLE.

1,153,592.

Specification of Letters Patent. Patented Sept. 14, 1915.

Application filed March 6, 1914. Serial No. 822,912.

To all whom it may concern:

Be it known that I, LEIGH S. BACHE, a citizen of the United States, and a resident of Boundbrook, in the county of Somerset 5 and State of New Jersey, have invented certain new and useful Improvements in Oilless Spindles, of which the following is a full, clear, and exact description, whereby anyone skilled in the art may make and use 10 the same.

The invention relates to oilless spindles and more particularly to the bearing for the spindle blade which said bearing may be adapted and utilized in any form of spindle desired.

The object of the invention is to provide a self-lubrication for the spindle blade due to the inherent qualities of the bearing upon and within which the blade runs, no oil bath 20 being required.

A further object is to provide for lubrication of the blade due to the heat generated by the spindle within the spindle bearing and to provide in conjunction therewith an 25 adjustment for the heat generating member of the spindle bearing.

Referring to the drawings: Figure 1 is a 30 view in side elevation of a spindle of well-known type. Fig. 2 is a vertical sectional view through the spindle, cup, whirl, bolster and step bearing on enlarged scale. Fig. 3 is a similar sectional view showing the bolster and step in one piece. Fig. 4 is a 35 detail sectional view illustrating a modified form of adjustment for the heat generating plug.

There is illustrated herein a well-known and ordinary type of spindle embodying a 40 whirl, spindle blade, bolster and step bearing and cup inclosing the bolster and step bearing. In such devices, ordinarily, the cup serves as an oil cup and serves as a holder for a lubricating bath in which all 45 of the several parts are immersed.

It has not been unusual to provide bolsters and steps of various types including metal, fibrous packings and wicking combined with metals but with any of the types of bearings known an oil bath has been provided in the oil cup for maintaining proper lubrication of the parts to keep the spindle bearings cool.

The principal object of the present invention is to obviate the necessity of liquid 55 lubricants and to provide for an adjustment

of the parts of the self-lubricating bearing formed of fibrous material completely and thoroughly impregnated with fatty acids, waxes and mineral and vegetable oils.

The bearing formed from the material 60 hereinafter described, gives a perfect and complete lubrication to the spindle and this is effected by providing for a combined metallic and fibrous step either separate from or combined with the bolster and made adjustable so that there is no possibility of the 65 blade cutting into the lower end of the bolster or step to such an extent as to cause undue friction of the blade within the bolster bearing. To this end, the lower end of 70 the bolster or step is provided with a metallic plug upon which the end of the spindle rests and owing to the friction, under rapid rotation, just sufficient heat is developed to withdraw a thin film of lubricant 75 from the bolster which will be adequate for lubricating surfaces and yet will not flood. To preclude the possibility of the spindle settling the metallic plug is made adjustable and therefore there is no possibility of the 80 spindle settling into the bolster to thereby produce undue friction and heating.

Referring to the drawings, the numeral 1 denotes the spindle blade which is provided with the usual whirl 2 which encircles the 85 upper end of the oil cup 3. This oil cup is mounted in the spindle rail 4. Within the oil cup and surrounding the lower end 5 of the spindle, there is arranged a tapered 90 fibrous bushing or bearing 6, which takes the place of the ordinary bolster bearing and the end of the spindle which is left quite blunt as indicated at 7 bears directly upon a metallic plug 9 which is located in the end 95 of the bolster as illustrated in Fig. 3 or in a step bearing 8 as illustrated in Fig. 2. This metallic plug is preferably of very hard steel and registers with the end of the spindle. It extends an appreciable distance into the fiber surrounding it and may be of 100 any desired length depending upon the depth of the step bearing or depending upon the depth of the fibrous bearing extending below the bolster.

The hardened plug would ordinarily be 105 sufficient to prevent wear and also to prevent the beveled sides of the spindle blade portion 5 from settling into the bolster. It has been found, however, that for the best results, a compensation must be effected for 110

any wear whatsoever in order to secure the longest life for the parts and to provide for this, without detracting from the proper generation of heat, to withdraw the lubricant from the fiber, an adjusting device is provided for raising the metallic plug 9, as any wear is occasioned either upon the end of the plug or the end of the spindle.

Both the bolster and step portions of the bearing are impregnated with a lubricant which has a high melting point far in excess of the ordinary heat developed by the spindle running under proper lubricated conditions. The lubrication of the parts is perfect so long as the spindle is maintained in predetermined bearing position and therefore to take up any wear, the adjusting device serves to lift the plug 9 and permits utilization of the fibrous bolster and step for a maximum period of time. The lubricant does not exude from the bearing sufficiently to be dissipated but simply forms a film which gives the proper lubrication for the bearing when the right amount of heat is generated. As the spindle, due to its contact with the metallic plug, generates just sufficient heat to draw the film of lubricant from the impregnated fiber, the bearing runs cool and there is therefore no further exuding of the lubricant from the bearing with the result that there is no over-heating in view of the perfect lubrication. Furthermore, there can be no throwing of oil and the bolster and step may be renewed and adjusted without soiling the spindle frame or goods in course of manufacture. A particular feature of the present invention is to provide for the adjustment of the heat generating plug 9 and this is conveniently effected through the medium of a screw 10 extending up through the bottom of the oil cup and through the fibrous bearing 8 as illustrated in Figs. 2 and 3 or through a conically pointed screw 11 introduced through the side of the oil cup and with its point projecting just under the lower edge of the plug 9.

It is preferred to so arrange the screw 10 that there will be no liability of conducting heat from the heat generating plug 9 to the larger body of metal of the oil cup and this may be effected by using an adjusting screw of fibrous material of a non-conducting nature or preferably by insert-

ing between the upper end 12 of the adjusting screw and the lower end 13 of the plug 9, a pellet of insulation 14. This may be of porcelain, glass or any good non-conductor of heat and serves merely to prevent dissipation of heat induced in the plug 9 and its radiation to the metallic parts of the oil cup.

In Fig. 3 the bolster and step are illustrated as in one piece 15 with the heat generating plug 16 projecting up into the bottom of the fibrous bolster and step and registering with the end of the spindle blade. This plug is made adjustable by the screw 17.

In Fig. 4 there is a modified form of adjustment wherein the adjusting screw 11 serves not only to raise the heat generating plug but prevents dislodgment and movement of the fibrous bearing part 18.

Obviously, the exact detail of adjusting device may be varied to a considerable extent without departing from the spirit or intent of the invention which contemplates the ready adjustment of the heat generating plug to compensate for any and all wear which may be developed between the plug and the spindle.

What I claim as my invention and desire to secure by Letters Patent is:

1. A spindle bearing embodying a bolster and step formed of fibrous material impregnated with a lubricant and having a metallic plug embedded in the fibrous material and with its end in contact with the end of the spindle whereby said spindle and plug generates sufficient heat to withdraw lubricant from the fibrous bearing, and a heat insulated adjusting device for moving said plug. 85

2. A spindle bearing embodying a bolster and step formed of fibrous material impregnated with a lubricant and having a metallic plug embedded in the fibrous material and with its end in contact with the end of the spindle whereby said spindle and plug generate sufficient heat to withdraw lubricant from the fibrous bearing, and a heat insulating adjusting device for moving said plug with reference to the fibrous bearing and spindle blade. 95 100
